UNITED STATES PATENT OFFICE

FRANK H. PETERSEN, OF DENVER, COLORADO

HORN WEIGHT FOR CATTLE

Application filed February 16, 1929. Serial No. 340,593.

My invention relates to improvements in horn weights for cattle.

The main object of the invention is to provide a horn weight comprising the weight proper and the clamping elements, said weight and clamping elements being assembled at the time of manufacture and supplied to the trade in assembled form, thus preventing the loss of parts and enabling the weights to be easily and quickly placed upon the horns of cattle and clamped thereon in the desired position.

Further, to provide a horn-weight, which will accommodate itself to the curve of the horn; which is provided with clamping means which will not produce a flattened surface on the horn or otherwise mar the same, and which also provides for a free circulation of air around the horn at the point where it is clamped thereon.

These objects are accomplished by the character of weight illustrated in the accompanying drawings in which,

Fig. 1 is a central vertical sectional view of the weight taken longitudinally of the horn-receiving hole therethrough, the clamping means being omitted.

Fig. 2 is a sectional view thereof on the line 2--2 of Fig. 1.

Fig. 3 is a view of the weight in line with the horn-receiving hole therein, showing the clamping means in connection therewith.

Fig. 4 is a central vertical sectional view through the weight taken transversely of the horn-receiving hole, and showing the clamping means in connection therewith.

Fig. 5 is a horizontal sectional view on the line 5—5 of Fig. 3.

Fig. 6 is a side view of the clamp block.

Fig. 7 is a bottom view of the same, and

Fig. 8 is a side edge view of the key for locking the clamp block in the weight.

Referring to the accompanying drawings:

The numeral 1 designates the horn weight which is preferably spherical in form but which may be of other forms having a rounded surface, and they may be made in sizes varying from a half pound to three or more pounds to meet requirements in the different stages of the horn-bending process. The

weight has a tapered hole 2, extending through the same, the axis of which is eccentric to the axial center of the weight, and the upper half of this hole is of an inverted V-shape in cross section, this construction permitting the horn, which is slightly curved, to pass through the hole, as the outer curve of the horn will lie in the V-shaped part of the hole, thus permitting the curved horn to fit in the straight-sided hole. The wall of the weight is thinnest at the point corresponding to the upper side of the hole 2, and thickest at the diametrically opposite point, which for convenience, will be termed the lower side of the weight. In casting the weight, a circular hole 3 extends into the lower side thereof and opens into a square recess 4 of sufficient depth to receive a nut of suitable size, as will later be seen, and the recess 4 opens into a circular recess 5 of greater diameter than the recess 4, and from the recess 5, a substantially square opening 6 intersects the horn receiving hole 2; the opening 6 being slightly larger than the square recess 4. The recess 4 is positioned so that two of its opposite corners are in line with the axis of the hole 2, and the sides of the opening 6 are parallel with those of the opening 4. From the larger end of the hole 2 and at the lowest point thereof, is formed a dove-tailed keyway 7 which intersects the opening 6, the bottom of said keyway coinciding with the upper wall of the circular recess 5, as clearly shown in Fig. 1.

The clamping elements comprise a nut 8, a clamp block 9, and a machine screw 10. The block 9 is circular in form and flat on its top and bottom sides; its top side being serrated or formed with a plurality of pointed teeth 11, and it is also formed with a vertical V-shaped groove 12 on one side, and with two oppositely projecting lugs 13 which are flush with the bottom of the block and about one-third of its thickness.

The weights are supplied to the trade with the clamping members assembled and locked within the weight, and these members are assembled and locked against accidental displacement in the following manner: The nut 8 is inserted in the larger end of the horn

hole 2 and passed through the opening 6 and circular recess 5 and into the square recess 4 which holds it from turning. The block 9 is then inserted in the hole 2 and one of its lugs 13 is passed under the upper wall of the circular recess 5 and its other lug passed down through the keyway groove 7 and into the recess 5, and the block then rests upon the nut 8. The block is then given a quarter turn to cause its groove 12 to register with the keyway 7 and a key 14 having a V-shaped forward end 15 is driven into the keyway, its forward end projecting into the groove 12 in the block. The key prevents turning of the block, and the lugs 13 on the block extend under the upper wall of the recess 5 and prevent the block from becoming disconnected from the weight but permit upward movement of the same. The V-shaped end of the key is slightly upturned as shown in Fig. 8, and this prevents the possibility of the key passing under the clamping block, if the block should be at the limit of its upward movement in the recess 5 when the key is driven into the keyway. The side edges of the key are beveled to correspond to the sides of the dovetailed keyway 7, and the key fits so tightly in the keyway that it must be forcibly driven in place and therefore cannot work loose. The screw bolt 10 is inserted in the hole 3 and screwed into the nut 8 and the weight is then ready to be attached to a horn. In practice, the size of the weights to be used is determined by the age of the cattle, as well as by the sizes of their horns; the purpose of the weights being to cause the horns gradually to turn downward and inward rather than upward and outward, which is their natural tendency, thus not only giving uniformity in respect to horns, to all the cattle of a herd, but at the same time eliminating the danger from gorings. The weights are placed upon the horns with the clamping members on the under side thereof, and the screws 10 are turned against the clamp blocks thereby clamping them against the horns and thus securing the weights thereon, and as the under sides of the weights are thicker and therefore heavier than the upper sides, they will remain in the positions in which they are clamped without turning upon the horns.

As the clamp block engages only a small part of the surface of the horn, the horn will not be flattened or straightened under the clamping action. Recesses 16 are formed in opposite sides of the face of the horn receiving hole 2, and these recesses not only reduce the contact surface between the weight and horn, but they also permit a free circulation of air around the horn within the weight thereby preventing sweating.

Having described my invention, what I claim as new and desire to secure by Letters Patent, is:

1. A horn weight comprising a metal body having a tapered horn-receiving hole, a circular recess in the body, a square recess in the bottom of the circular recess, a hole extending out through the bottom of the square recess, and an opening intersecting the horn-receiving hole and the circular recess, and coinciding with the square recess, said circular recess being of greater diameter than said opening; a nut in the square recess, a block in the circular recess having opposite projecting lugs on its lower end of less thickness than the depth of said recess, which are adapted to engage the upper wall of said recess to prevent disconnection of the block from the recess, said block having a serrated upper end, means for preventing rotation of said block, a screw in the nut which is adapted to be turned against the block thereby to clamp the same upon the horn to secure the weight thereon. 70 75 80 85

2. A horn weight comprising a metal body having a tapered horn-receiving hole the upper half of which is of an inverted V-shape in cross section, said body having a square recess in lower portion and a hole extending out through said square recess, a circular recess above and communicating with the square recess and of greater diameter, and an opening intersecting the circular recess and the horn-receiving hole and coinciding with the square recess, a keyway being formed in the lower side of the horn-receiving hole which intersects the said opening; a nut in the square recess; a block in the circular recess having a serrated upper end, a groove in one side thereof and opposite projection on its lower end of less thickness than the depth of the said circular recess and adapted to prevent disconnection of the block from the recess by engagement with the upper wall of said recess, a key in said keyway which engages the groove in said block to prevent turning of the same, and a screw in said nut to engage the block 100 105 110 115 to force the same against the horn thereby to secure the weight thereon.

In testimony whereof, I affix my signature
FRANK H. PETERSEN.
